Patented July 2, 1912.

UNITED STATES PATENT OFFICE.

BERRY C. MOXLEY, OF HOQUIAM, WASHINGTON.

SPARK-ARRESTER.

1,031,570.

Specification of Letters Patent.

Patented July 2, 1912.

Application filed February 15, 1912. Serial No. 677,656.

To all whom it may concern:

Be it known that I, BERRY C. MOXLEY, a citizen of the United States, residing at Hoquiam, in the county of Chehalis and State of Washington, have invented a new and useful Improvement in Spark-Arresters, of which the following is a specification.

My invention is an improvement in spark arresters, and has for its object the provision of a simple inexpensive device of the character specified, capable of attachment to any stack without change in the same, and without diminishing the draft, by means of which the unconsumed solid matters ejected from the stack will be held in the arrester.

In the drawings, Figure 1 is a vertical section of the spark arrester positioned on a smoke stack and embodying the invention or improvement. Fig. 2 is a section on the line 2—2 of Fig. 1, and Fig. 3 is a plan view of the damper.

The present embodiment of the invention is shown in place on the upper end of a stack 1, and comprises a collar or cylinder 2, seated around the upper end of the stack, and secured to the stack, by means of bolts and nuts 3. A plurality of bracket arms is secured in spaced relation to the collar, each arm consisting of two laterally offset vertical portions 4 and 5, connected by a horizontal portion 6. The portion 4 of each bracket is secured to the outer face of the ring, by bolts or rivets 7, and the portions 5 and 6 of each bracket are braced by a brace 8. End 9 of the brace is bent at an angle to the main portion, as shown at 9, to fit against the inner face of portion 5, and against the upper face of portion 6, and bolts 10 are passed through the said portions and the ends 9, and are engaged by nuts 11. The upper end of each bracket 4—5 is provided with an inwardly extending arm 12, approximately parallel with the connecting portion 6, and each arm extends radially inward, beyond the collar 2. A covering 13 of perforate material, as for instance wire gauze, is arranged outside the brackets, and the arms 12, extending from the inner ends of the said arms 12 to approximately the center of collar 2. The lower end of the covering, which is of cylindrical form around the portions 5 of the brackets, and frusconical or tapering below the said portions, is secured to the collar by a split clamping ring 14. The ends of

the ring are provided with radial lugs 15, which may be clamped together by a bolt or like means. The upper end of the covering fits closely on the arms 12 and may be secured to the said arms in any suitable manner. A ring 16 is arranged below the arms 12, at their inner ends, and the inner edge of the ring is flush with the inner ends of the arms. An angle bracket 17—18 is secured to one of the arms 12, by means of bolts or rivets 19, engaging the arm and the portion 17 of the bracket, and the other portion 18 of the bracket is provided with a bearing 20. A lever 21 is pivoted to the bearing, intermediate the ends of the lever, and an operating rod 22 is engaged with a ring 23, at the outer end of the lever. A cross bar 24 is arranged transversely of the collar 2, at its upper end, each end of the bar being bent downwardly at a right angle to the main portion as shown at 25, and secured to the inner face of the collar by bolts and nuts 26. The cross bar is provided with a central bearing 27, at the axis of the stack, and a rod 28 is slidable in the bearing. A link 29 connects the upper end of the rod to the inner end of the lever 21. The upper end of the rod is split to receive one end of the link, and a pin 30 passes through the link and end of the rod. The upper end of the link is forked to engage the lever end, and a pin 31 passes through the arms of the fork and the link. It will be evident that when the lever is swung by the rod 22, the rod 28 will be raised or lowered, depending upon the direction of movement of the lever. A cover or damper plate 33 of circular form is connected to the rod, by means of the mechanism shown in Fig. 3. The plate is provided with a central opening for the rod 28, and the said rod is provided with a transverse opening, through which passes a pin 34. A bearing 35 is secured to the upper face of the plate, on each side of the rod, and the ends of the pin are journaled in the bearings. By means of the lever 21, the plate may be moved from the full line position of Fig. 1, to either of the dotted line positions of the said figure. Since the plate is free to swing laterally within limits, it will always seat closely on the upper end of the collar, or against the under side of ring 16. When seated on the upper end of the collar, the stack is closed, and when against the ring the opening through the perforate

hood is closed, so that all of the products of combustion from the stack must pass through the hood.

The plate 33 may be placed at any intermediate position between the collar and the ring, to increase or diminish the draft, and in whatever position it may be placed, the cinders and sparks are effectually cut off from the outlet at the top. Any solid substance passing from the stack will strike the plate and will fall back into the stack, or into the frusto-conical portion of the hood.

It will be evident that the device is not only a spark arrester, but also a damper, by means of which the draft may be regulated. The defect of the usual form of spark arrester is that the draft is lessened to such an extent that it is difficult to start a fire and to keep it going after starting.

With the improvement the draft is not lessened, the annular passage around the plate 33 being of as great aggregate area as that of the stack, or even greater. In addition the perforate hood increases this area. When starting the fire, the damper or plate 33 is lowered to approximately the position of Fig. 1. After the fire is burning, the plate is raised to close the opening from the hood.

The device may be applied to any stack, without change in the stack, and affords a perfect protection. The improvement is in fact a hood of perforate material inclosing the top of the stack and having an outlet in line with the axis of the stack, and a damper for closing the outlet, movable between the end of the stack and the outlet.

I claim,

1. A spark arrester comprising a collar adapted to fit the top of the stack, and having means whereby it may be secured to the stack, a plurality of brackets secured to the collar, each comprising two connected radially offset vertical portions, one of said portions being secured to the collar, each of the other of the said portions having a radial inwardly extending arm at its upper end, a ring connecting the inner ends of the arms, a hood of perforate material supported on the brackets, said hood being of approximately cylindrical form, the upper end thereof being secured to the ring, a split ring for clamping the lower end to the collar, and a damper plate movable between the upper end of the collar and the ring, said plate being circular and having a central opening, a rod passing through the opening, a cross bar arranged transversely of the collar and provided with a central bearing for the rod, a bracket arm on one of the brackets, a lever pivoted intermediate its ends to the bracket arm, an operating rod connected to the outer end of the lever, a link connecting the inner end to the upper end of the rod, a pair of alined bearings

arranged transversely of the plate, and a pin journaled in the bearings, the rod having a transverse opening for the pin.

2. A spark arrester comprising a collar adapted to fit the top of the stack, and having means whereby it may be secured to the stack, a plurality of brackets secured to the collar, each comprising two connected radially offset vertical portions, one of said portions being secured to the collar, each of the other of the said portions having a radial inwardly extending arm at its upper end, a ring connecting the inner ends of the arms, a hood of perforate material supported on the brackets, said hood being of approximately cylindrical form, the upper end thereof being secured to the ring, a split ring for clamping the lower end to the collar, and a damper plate movable between the upper end of the collar and the ring, said plate being circular and having a central opening, a rod passing through the opening, a cross bar arranged transversely of the collar and provided with a central bearing for the rod, a bracket arm on one of the brackets, a lever pivoted intermediate its ends to the bracket arm, an operating rod connected to the outer end of the lever, a link connecting the inner end to the upper end of the rod, and a connection between the rod and the plate.

3. A spark arrester comprising a collar adapted to fit the top of the stack, and having means whereby it may be secured to the stack, a plurality of brackets secured to the collar, each comprising two connected radially offset vertical portions, one of said portions being secured to the collar, each of the other of the said portions having a radial inwardly extending arm at its upper end, a ring connecting the inner ends of the arms, a hood of perforate material supported on the brackets, said hood being of approximately cylindrical form, the upper end thereof being secured to the ring, a split ring for clamping the lower end to the collar, and a damper plate movable between the upper end of the collar and the ring, said plate being circular and having a central opening, a rod passing through the opening, a cross bar arranged transversely of the collar and provided with a central bearing for the rod, a connection between the rod and the plate, and means for moving the rod vertically.

4. A spark arrester comprising a collar adapted to fit the top of the stack, and having means whereby it may be secured to the stack, a plurality of brackets secured to the collar, each comprising two connected radially offset vertical portions, one of said portions being secured to the collar, each of the other of the said portions having a radial inwardly extending arm at its upper end, a ring connecting the inner ends of the

arms, a hood of perforate material supported on the brackets, said hood being of approximately cylindrical form, the upper end thereof being secured to the ring, a split 5 ring for clamping the lower end to the collar, and a damper plate movable between the upper end of the collar and the ring, and means for moving the plate.

5. A spark arrester comprising a substantially cylindrical hood of perforate material 10 having its ends open and reduced in diameter to approximately the diameter of the stack, means for connecting the lower end of the hood to the stack, an imperforate damper plate movable between the ends of 15 the hood for closing either end, said plate

being of less diameter than the diameter of the hood, and means for moving the plate.

6. A spark arrester comprising a substantially cylindrical hood of perforate material 20 having its ends open and reduced in diameter to approximately the diameter of the stack, means for connecting the lower end of the hood to the stack, an imperforate damper plate movable between the ends of 25 the hood for closing either end, and means for moving the plate.

BERRY C. MOXLEY.
